ATTORNEY

UNITED STATES PATENT OFFICE.

RANDALL T. VAN VALKENBURG, OF DAYTON, OHIO.

DESIGN FOR A CHURN-DASH.

SPECIFICATION forming part of Design No. 28,428, dated March 29, 1898.

Application filed February 7, 1898. Serial No. 669,454. Term of patent 14 years.

To all whom it may concern:

Be it known that I, RANDALL T. VAN VALKENBURG, a citizen of the United States, residing at Dayton, in the county of Montgomery and State of Ohio, have invented and produced a new and original Design for a Churn-Dash; and I do declare the following to be a full, clear, and exact description of the same, reference being had to the accompanying drawings, forming a part thereof.

Figure 1 is a side elevation of a churn-dash, showing my new design. Fig. 2 is a lower plan view.

As is shown in the accompanying drawings, the leading or material feature of my new design consists of a churn-dash, the body A of which is of a conical or bell shape, so that a substantially smaller area of opening is provided at the top than at the bottom. The lower end of said cone has a series of blades

B projected out therefrom substantially on the angles shown in the drawings. The upper end of said cone is joined to a hub or socket C by a series of bars D. The lower end of the said hub is on a plane above that of the upper end of the cone, so that the bars D occupy an incline in reaching from said cone to the hub. The upper sides of the said bars D taper in the same direction or in the direction in which the blades B lie.

30

Having described my invention, I claim as new and desire to secure by Letters Patent—

The design for a churn-dash substantially as shown and described.

In testimony whereof I affix my signature 35 in presence of two witnesses.

RANDALL T. VAN VALKENBURG.
